UNITED STATES PATENT OFFICE.

ORA M. BOORMAN, OF OSHKOSH, WISCONSIN.

HOLDER.

1,108,687.

Specification of Letters Patent. Patented Aug. 25, 1914.

Application filed September 3, 1913. Serial No. 787,972.

To all whom it may concern:

Be it known that I, ORA M. BOORMAN, a citizen of the United States, residing at Oshkosh, in the county of Winnebago and State of Wisconsin, have invented new and useful Improvements in Holders, of which the following is a specification.

This invention relates to manuscript holders and more particularly to manuscript holders adapted for use in connection with typewriter machines.

The principal object of the invention is to provide a simply constructed, cheap and durable device of this character which permits the support of the manuscript or note book immediately in front of the operator, thereby avoiding the necessity of turning the eyes to the left or right to read the notes.

Another object of the invention is the provision of a simple and efficient manuscript holder in which the manuscript or note supporting rack is adjustable to different inclinations and heights and also toward and away from the operator so that the best possible view of the notes may be obtained.

Another object of the invention is to promote speed and accuracy. With the manuscript directly in front, the necessity of stopping to find the place on the manuscript to be copied each time the eyes glance from manuscript to typewriter is practically eliminated. With the manuscript on the holder, the shift can be operated without taking the eyes from the notes, and should it be necessary to look at the keys, the place on the notes can be found again much more quickly than when turning the head to the side.

Further objects of the invention will appear as the following description is read in connection with the accompanying drawing, which forms a part of this application, and in which:

Figure 1 is a front elevation showing the association of the device with an ordinary typewriter, the typewriter being indicated in dotted lines. Fig. 2 is a side elevation with the typewriter similarly indicated. Fig. 3 is a top plan view. Fig. 4 is a horizontal section taken on the line 4-4 of Fig. 1.

Referring more particularly to the drawing, the device is constructed of two uprights 1 and 2, both of which are constructed alike and with a forwardly extending supporting foot. The standards or uprights are connected together by a plurality of cross bars 4 and each is provided with a rearwardly

curved portion 5 which connects the lower part of the standard with the forwardly offset upper part so as to bring the upper part indicated at 6 over the typewriter. Each standard or upright is provided with a forwardly extending arm 7 projecting at right angles from the standard and provided with a slot 8, a right angular continuation 9 of which extends vertically through the upright, as indicated.

Bridged between the arms 7 of the uprights 1 and 2 is a shaft 10 upon which is secured a rack frame 11 provided with a shelf 12 at its lower end. The shaft 10 is provided with enlarged rigid collars 13 and with reduced threaded ends upon which set screws 14 are mounted. This arrangement permits the free rotation of the shaft within the slots 7, 8 and 9 and also its retention in any given position. Projecting outwardly from the frame at one side are two lugs 15 which act as manuscript or book guides and at the upper end of the frame there is secured a leaf spring 16 by which the manuscript or book may be held upon the rack.

As shown, the supporting feet are connected together by a bridge piece 17 which extends beneath the typewriter, as shown, and each foot is provided with a set screw 18 adapted to engage the sides of the typewriter for securing the holder against displacement. As shown, the cross bars 4 are arranged adjacent the bottom and top of the uprights and, therefore, do not interfere with the insertion of paper in the typewriter and as the rack is located immediately above the typewriter directly in front of the operator the necessity of constantly keeping the eyes turned to the left or right is obviously eliminated. Furthermore, it will be seen that by the construction a wide range of adjustment is provided for the rack and thereby the proper arrangement for each individual operator may be obtained.

What is claimed is:

1. A manuscript holder for typewriters comprising supporting uprights adapted to extend upon opposite sides of the machine, means for connecting the uprights together, means for securing the uprights to the machine, integral arms projecting horizontally from the uprights and having slots therein which are continued throughout a portion of the uprights, a shaft rotatably and adjustably mounted in said slots and a manuscript holding rack carried upon the shaft.

2. In a manuscript holder for typewriters, a pair of uprights having forwardly offset vertical portions and horizontally arranged forwardly extending supporting feet, said 5 supporting feet adapted to be arranged upon opposite sides of the typewriter, means carried by the supporting feet for attaching the device to the typewriter, means for connecting the uprights together, integral arms projecting horizontally from the upper portions 10 of the uprights, said arms being provided with slots which are continued throughout a portion of the uprights, a shaft rotatably

mounted and adjustably arranged in the slots, means for locking the shaft against 15 rotation and adjustment in the slots, a manuscript holding rack secured to the shaft and means for holding the manuscript on the rack.

In testimony whereof I affix my signature 20 in presence of two witnesses.

ORA M. BOORMAN.
